HEAT SENSITIVE DEVICE

Allen H. Keyser, Worcester, Pa., assignor, by
mesne assignments, to Minneapolis-Honeywell
Regulator Company, Minneapolis, Minn., a cor-
poration of Delaware

Application September 27, 1947, Serial No. 776,572

3 Claims. (Cl. 136—4)

1

This invention relates to heat measurement and more particularly to a plurality of thermocouples connected in series to form a thermopile.

It is an object of this invention to provide a heat sensitive element suitable for measuring animal body temperature by insertion into a natural cavity of, or into an incision in the body of an animal, such as a guinea pig, used for laboratory experiments.

It is a further object of this invention to provide a thermopile in which each thermocouple is insulated from the other thermocouples by a sleeve of loosely woven glass fabric, a tube of loosely woven glass fabric supporting all the sleeves, and a lump or solid body of plastic impregnating and embodying the thermocouples, the glass sleeves and the glass tube and completely containing them.

The various features of novelty which characterize this invention are pointed out with particularity in the claims annexed to and forming a part of this specification. For a better understanding of the invention, however, its advantages and specific objects obtained with its use, reference should be had to the accompanying drawings and descriptive matter in which is illustrated and described a preferred embodiment of the invention.

Of the drawings, of which Figs. 1 to 4 are on a greatly enlarged scale, Fig. 1 is a view of a longitudinal cross section with parts broken away transversely to reduce the overall length of the figure. The left hand side of the figure is taken on a substantially diametric line 1—1 of Fig. 2. The central part of the figure is taken on a curved line 1A—1A of Fig. 3 just above the glass sleeves, the outer layers being removed for clarity. The right hand part of the figure is taken on a line 1B—1B of Fig. 4 just outside one of the thermocouples. The broken away sections are viewed in the direction of the arrows applied to the above mentioned section lines.

Fig. 2 is a transverse cross section on line 2—2 of Fig. 1 as viewed in the direction of the arrows.

Fig. 3 is a transverse cross section on line 3—3 of Fig. 1 as viewed in the direction of the arrows.

Fig. 4 is a transverse cross section on line 4—4 of Fig. 1 as viewed in the direction of the arrows.

Fig. 5 is a longitudinal elevation on full scale.

Fig. 6 is a partial longitudinal cross section substantially of the same parts shown in the left hand side of Fig. 1 and with the middle part broken away substantially in the line 6—6 of Fig. 3 as viewed in the direction of the arrows.

Fig. 7 is a phantom or partial perspective view in transverse cross section as viewed in the direction of the arrows applied to the line 7—7 of

2

Fig. 6 with the outer layers indicated by broken lines.

One preferred embodiment of this invention, selected from among others for illustration in the drawing and description in the specification, is as follows.

Six wires, 11, 12, 13, 14, 15, 16, each about five feet in length are provided. Three of these wires are of one metal, such as copper, and the other three of another metallic composition, such as constantan. While copper and constantan are the preferred materials for these wires, any pair of dissimilar metals or alloys may be used provided they give an appreciable voltage when joined together at one end and heated, while the other end remains relatively cool. The odd and even numbered wires are joined together at one end by having the softer wire coiled about the harder and soldered, welded and otherwise united into a helically shaped thermocouple, of which one is seen at 17 in Fig. 1.

Each of the wires has on it, except at the bare end at which it is joined to another wire, a layer of threads of insulation 18, such as cotton thread.

25 These insulating layers may, if desired, be of different colors so as to identify the individual wires. A relative small and short sleeve of loosely woven glass fabric is placed around each thermocouple and the adjoining layers of insulation 18.

30 These sleeves are marked 19, 20 and 21 on the drawings. The sleeves 19, 20 and 21 extend for substantially the entire length of the thermometer rearwardly or to the left as seen in Fig. 1 from the thermocouples 17. At their rear or opposite ends from the thermocouples 17, the ends of the sleeves adjoin the end of a layer of rubber-like sheathing or insulation 22 which surrounds the insulated wires and forms them into a cable. The wires and their insulating coverings may be coiled or wound into a helical form within the sheathing 22.

35 A ring or ferrule 23 of metal is placed over the end of the sheathing 22. One or both ends of the ferrule 23 may be spun over or clinched, as indicated at 24, to retain the ferrule 23 on the sheathing 22 and to seal the cable against the entrance of air or moisture. A relatively large and long tube 25 of loosely woven glass fabric is placed over the ferrule 23 and in contact with a portion of the outer surfaces of the sleeves 19, 20 and 21.

40 A solid block or body of plastic 26, such as an unsaturated polyester resin type, is formed on the surfaces of the thermocouples 17, the sleeves 19, 20 and 21, the ferrule 23, and the tube 25. This body of plastic impregnates any openings in the sleeves and in the tube and completely imbeds and surrounds the other elements. The outer surface of the plastic body 26 is smoothed off so that there is provided a stiff, light, smooth

and otherwise attractive and desirable protecting body for the thermopile and the protecting glass sleeves surrounding the individual thermocouples and the glass tube.

The process of manufacturing this thermometer is as follows: The ends of the wires 11-16 are dipped in clear varnish and dried in air. The layer of insulating fabric 18 is then removed from each of the wires 11-16 for about one-half inch from one end. The ends of the individual wires 11-16 are then cleaned to a bright metallic surface, twisted in a helical coil and welded together. The individual thermocouples thus formed are insulated with one dip coat of suitable insulation and allowed to dry in air for one half hour. The ferrule 23 is then slipped over and firmly fastened on the end of the rubber insulating coating 22. The smaller, shorter sleeves 19, 20, and 21 are next slipped over each of the thermocouples 17 and the wires with their insulating coating 18 which form the leads to the thermocouples. The reinforcing tube 25 of loosely knit glass fabric is then placed longitudinally over the thermocouples and the smaller shorter glass sleeves surrounding them. The end of the glass fibre tube 25 overlies at least a portion of the ferrule 23. The parts thus assembled are placed in a suitable mold, such as a small glass tube. One end of this glass tube is dipped beneath the surface of fluid plastic, such as unsaturated polyester resin type. A vacuum is applied to the upper or opposite end of the solid glass tube so that the plastic is drawn up into the tube around the thermocouples, the glass sleeve and the glass tube. The plastic is then allowed to set and harden. This setting and hardening may be facilitated by baking with heat. When the plastic body is sufficiently hard to withstand handling, it is removed from the mold or glass tube and any rough edges or projecting portions of the outer surface of the plastic body 26 are removed. There is thus formed a thermometer including a thermopile which can be used in a cavity or incision in the body of an animal, without unnecessary irritation. In use, the thermometer remains within the body of the animal for a period of one half hour or more.

While in accordance with the provisions of the statutes, I have illustrated and described the best forms of the invention now known to me, it will be apparent to those skilled in the art that changes may be made in the form of the apparatus disclosed without departing from the spirit of the invention as set forth in the appended claims, and that in some cases certain features of the invention may sometimes be used to advantage without a corresponding use of other features.

Having now described my invention what I claim as new and desire to secure with Letters Patent is as follows:

1. A temperature-measuring device for insertion into the body of an animal, said device including a solid mass of set unsaturated polyester resin type plastic of low heat conductivity having a smooth outer surface, a stiffening layer formed of a tube of loosely interlaced threads of glass fibre embedded in the mass of plastic, a metallic ring embedded in the mass of plastic beneath a portion of the tube of glass fibre, a tubular layer of flexible insulating material pro-

jecting into the mass of plastic and closely encircled by the metallic ring, a plurality of tubular insulating coverings twisted together within the tubular coating, a plurality of wires of at least two different metallic materials each enclosed within one of said coverings, thermocouples formed of the ends of pairs of said wires of different material intimately joined together to form "hot" junctions, and a plurality of sleeves of loosely interlaced threads of glass fibre, said sleeves being of smaller diameter and shorter length than said tube of glass fibre and each embedded in the mass of plastic and encircling one of said thermocouples and a portion of the two tubular insulating coverings leading to the thermocouple so that said sleeves insulate the thermocouples and the adjacent portions of the tubular insulating coverings for the wires forming each thermocouple from the other thermocouples and pairs of wires.

2. A temperature sensing device including, a cable formed of a number of wires each having a layer of insulation on it and coiled about one another within a flexible insulating sheath, a ferrule circumscribing one end of each sheath, the ends of a pair of said wires of different metallic materials being united together to form a heat-responsive source of small voltage, a thickness of loosely knit glass textile girdling the ends of the wires, and a cohesive lump of permanently hardened plastic enveloping the ends of the wires and of their coatings and the sheath, the ferrule and the textile.

3. A temperature sensing device made up of a plurality of wires of a metallic material and an equal number of wires of a different metallic material joined together in pairs at one end to constitute thermocouples; a relatively short sleeve of glass cloth encircling each thermocouple; a relatively long sleeve of glass cloth encircling all of the thermocouples; a layer of threads encircling each wire except at the end formed into a thermocouple; a layer of rubber encircling the wires and the layers of threads and forming them into a cable; a ferrule encircling the end of the rubber layer; and a solid mass or body of set unsaturated polyester resin type plastic surrounding the thermocouples and the glass sleeves and having a smooth outer surface.
